UNITED STATES PATENT OFFICE.

ALVA J. FISHER, OF EVANSTON, ILLINOIS, ASSIGNOR TO HURLEY MACHINE COMPANY,
OF CHICAGO, ILLINOIS, A CORPORATION OF ILLINOIS.

IRONING-MACHINE.

1,332,892.

Specification of Letters Patent.

Patented Mar. 9, 1920.

Application filed December 21, 1917. Serial No. 208,227.

To all whom it may concern:

Be it known that I, ALVA J. FISHER, a citizen of the United States, residing at Evanston, in the county of Cook and State 5 of Illinois, have invented certain new and useful Improvements in Ironing-Machines, of which the following is a specification.

My invention relates to an ironing machine and to the roll thereof and the object 10 thereof is to provide for such roll a pad of a certain character of fibrous material such as jute, whereby the numerous objections heretofore experienced in practical use with pads of other material are effect- 15 tually overcome.

In practice pads for ironing machines are made of felt, such as cotton, wool or hair felt, but all of these materials are open to objection. For instance, the cotton felt, 20 owing to the heat and dampness acting upon it becomes very hard and dense inasmuch as it holds the moisture coming from the clothes being ironed and in a short time becomes practically a solid roll. A roll of 25 seven inches in diameter will shrink to about six and one-half inches owing to the fact that the pad becomes packed solid.

In case of wool felt, the thickness thereof is about three-sixteenths of an inch as ordinary 30 used for this purpose and owing to this thickness there are only about five laps or thicknesses on a roll. As a result the first lap and the last lap cannot meet within about two inches, otherwise there would be 35 a ridge the entire length of the roll due to the fact that at this particular point there would be six laps or thicknesses instead of five. Sometimes the ends of the pads will overlap unintentionally and in this event 40 the roll will not do satisfactory work as it will scorch the material where the ridge exists, or the clothes will not be thoroughly ironed inasmuch as the shoe is held in contact with springs and consequently where 45 there is an excess thickness the shoe will be released as the ridge comes around and into contact with the shoe. Moreover, a wool felt pad burns very easily with a little excess of heat and soon becomes discolored 50 to a dark brown besides becoming packed very hard. This reduces the strength of the pad and will cause it to break off in pieces.

In the case of the hair felt, a pad made 55 therefrom is not strong and the result is

much the same as in the case of the wool felt, particularly as to becoming hard and packed and also as to permitting of only a few thicknesses to be applied owing to the thickness of the hair felt which is from 60 one-quarter to three-eighths of an inch. Moreover it is more difficult to apply on the roll than either the cotton or wool felt.

I have discovered that a fibrous material such as jute has the proper characteristics 65 and attributes to form a most efficient pad inasmuch as it overcomes all of the objections noted in respect to pads of the other materials mentioned, as well as other advantages as hereinafter noted and as 70 made apparent from the description of my new pad or illustration thereof in the drawing.

In the drawing Figure 1 is a side elevation of an ironing machine in which my 75 invention is embodied; Fig. 2 an end elevation thereof; Fig. 3 an elevation of the roll detached, showing the beginning of the operation of applying the pad thereto; Fig. 4 a cross section on an enlarged scale taken 80 on the line 4-4 of Fig. 3; Fig. 5 a detail elevation of a portion of the roll showing one of the retaining hooks; Fig. 6 a section on the line 6-6 of Fig. 5, and Fig. 7 a detail view of the fibrous material employed 85 for the pad.

In Figs. 1 and 2 I have shown the type of ironing machine to the roll of which my invention is applied. This ironing machine consists of a main frame 1 which supports 90 supplemental frames or end brackets 2. In these brackets is journaled the ironing roll 3 on whose periphery is formed or mounted the pad 4. The shoe 5 is pressed against the pad or rather against the clothes to be 95 ironed which are interposed between the shoe and the pad. This pressure is a yielding one owing to the pivotal mounting of the shoe and the provision of the springs 6, the details of which it is unnecessary to explain as they are of well known character.

The roll 3 may be of the usual construction but I prefer to make the same as shown in Figs. 3 and 4, providing it with a series of hooks 7 arranged at intervals along the 105 length of the roll for the purpose of engaging the inner end of the material of which the pad is formed.

The material of the pad is of the coarse woven character as shown at 8 in Fig. 7, 110

such material in practice being known as jute. This material is first applied to the hooks of the roll and wound therearound as many times as required to give the necessary thickness or diameter of pad. It is found in practice that such a pad will hold to its original diameter to whatever size it may have been built up to, which invariable diameter is of great importance inasmuch as it provides a uniform ironing surface.

Other advantages of the jute pad are that it is impossible to burn the same with the heat applied by the ironing machine shoe and that the dampness coming from the clothes being ironed penetrates and escapes through the pores of the jute pad, with the result that a sheet or tablecloth for instance can be ironed in about twenty-five per cent. of the time required when the other kinds of pads above mentioned are used. Moreover the pad retains its original characteristics particularly its pliability, so that it is not necessary as in the case of the other types of pad to remove and wash it. Furthermore the cost of the jute pad is only a fraction of the cost of the other kinds of pad.

In addition, the jute pad will not shrink

which is of considerable advantage inasmuch as the danger of the burning of the pad and goods being ironed is prevented. The ironing shoe being made of metal always retains its radius, and if the pad should shrink as happens to the old described forms of pads, the area of contact between the shoe and pad is thereby reduced, with the result that the pressure of the shoe remaining the same the greater pressure exerted on the lesser area causes burning of the pad. Also, the jute pad can be advantageously used in connection with rolls having a solid or impervious surface, wherein the only places where the moisture or steam can escape are between the top and bottom edges of the shoe. The jute pad permits this steam or moisture to pass through its pores and to escape adjacent these edges of the shoe.

I claim:

1. For the roll of an ironing machine a pad formed of jute wound therearound to provide a plurality of thicknesses.
2. In combination with an ironing machine roll having a solid or impervious surface, a pad formed of jute and applied thereto.

ALVA J. FISHER.
